UNITED STATES PATENT OFFICE.

WILLIAM R. SMITH, OF BUFFALO, NEW YORK.

ORDNANCE.

SPECIFICATION forming part of Letters Patent No. 790,664, dated May 23, 1905.

Application filed February 20, 1904. Serial No. 194,510.

To all whom it may concern:

Be it known that I, WILLIAM R. SMITH, of Buffalo, in the county of Erie and State of New York, have invented certain new and useful 5 Improvements in Ordnance, of which the following is a specification.

My invention relates to improvements in ordnance.

The object of my invention is to provide a 10 gun or other piece of ordnance with means whereby the bore and interior of the gun will be kept comparatively cool and which will permit of a ready cleansing of the bore as the projectile is fired.

15 To this end the invention consists in the improved construction and combination of parts hereinafter fully described, illustrated in the accompanying drawings, and particularly pointed out in the appended claims.

20 In the drawings, in which similar reference characters indicate similar parts in all of the views, Figure 1 is a central longitudinal sectional view of a gun, showing the general arrangement of the parts. Fig. 2 is an enlarged 25 sectional view of the breech portion of the gun.

In the drawings, 5 represents a gun having the usual bore 6 and firing-chamber 7, the rear of the latter being closed by a breech-block 8 of any preferred construction, it being understood that the block with the firing-pin in position therein substantially seals the firing-chamber, as usual in breech-loading ordnance. It is to be also understood that the gun may be of any type and adapted either for use with 35 fixed or loose ammunition.

Within the walls of the gun are formed openings 9, which are inclined in a direction relatively to the axis of the gun, said openings leading to the outer surface of the gun, at 40 which point provision is made for the attachment of a suitable connection 10 of a pipeline 11, which in turn is connected with a suitable air-compressing device. (Not shown.) Each of the openings 9 is provided with a 45 check-valve 12 of suitable character, the drawings showing such valve conventionally, it being understood that the valve is arranged to open toward the bore of the gun to permit of the entrance of the compressed air when desired, as hereinafter specified. The inner ends

of the openings will be preferably located at the bottom of the grooves forming the rifling of the gun, so as not to interfere with the passage of the projectile. The openings 9 are arranged at suitable intervals throughout the 55 length of the gun, as shown, all of the openings being in the walls of the gun and forward of the breech-block. The number of openings 9 is governed by the size, &c., of the gun, and the relative arrangement of such openings 60 may be made as desired. As heretofore pointed out, the openings 9 are inclined rearwardly. Hence the admission of the air is in the direction toward that taken by the projectile, thereby reducing any tendency to check the passage of the projectile, any tendency to the formation of a vacuum behind the projectile being eliminated by the admission of the air in a direction following that taken during the movement of the projectile. 70

In practice the admission of compressed air will be controlled by any suitable means, so that it may be admitted as soon as the explosion takes place, so as to cool the gun and force unexploded gases and flame out of the 75 muzzle.

While I have herein pointed out one of the forms in which my invention can be carried out, it is to be understood that I reserve the right to use such modifications thereof as may 80 be found desirable and which may fall within the spirit and scope of the invention as expressed in the accompanying claims.

Having thus described my invention, what I claim as new is— 85

1. A breech-loading gun having a plurality of inclined openings leading into the bore of the gun forward of the breech-block, and means for connecting said openings with a source of compressed air independent of the 90 gun.

2. A breech-loading gun having a firing-chamber and bore, and having openings leading to said chamber and bore, said openings being spaced longitudinally of the gun, and 95 means for introducing air to said openings.

3. In breech-loading ordnance, the combination with a gun having a firing-chamber and bore and openings leading to said chamber and bore, said openings being spaced longitudi- 100

nally of the gun, and means for introducing air under compression to said openings.

4. In breech-loading ordnance, the combination with a gun having a firing-chamber and bore and valved openings leading to said chamber, said openings being spaced longitudinally of the gun, and means for introducing air under compression to said openings.

5. In breech-loading ordnance, the combination with a gun having a firing-chamber and bore and rearwardly-inclined valved openings leading to said chamber, said openings being spaced longitudinally of the gun, and means for introducing air under compression to said openings.

6. A breech-loading gun having an opening through its body into the bore independent of the breech-block, and a source of compressed air connected with said opening, means being

provided for preventing back pressure being 20 communicated to the source of compressed air, and means whereby said source of compressed air may be charged independent of the gun.

7. A breech-loading gun having an inclined opening through its body into the bore, means 25 for connecting said opening with a source of fluid under pressure, means being provided for preventing back pressure being communicated to said source, and means whereby said source may be charged independent of the 30 gun.

In testimony whereof I have affixed my signature in presence of two witnesses.

WILLIAM R. SMITH.
